UNITED STATES PATENT OFFICE.

LEROY M. PORTER, OF PARCO, WYOMING.

AUTOMATIC PUMP VALVE.

Application filed March 23, 1926. Serial No. 96,765.

My invention has for its object to provide an automatic valve mechanism for use with single cylinder pumps, and duplex pumps, etc., and it has for its further object the provision of a valve which will be superior to others in that it will require little or no maintenance.

Generically the invention provides a valve unit comprising a casing-cylinder having heads with ports adapted to be connected to the pump and having suction and discharge ports, there being a stationary ported sleeve within the casing and a free or floating sleeve within the ported sleeve and itself having ports to register, at times, with those of the stationary sleeve, and be actuated by the fluid pressure from the pump to shift accordingly as the piston of the pump moves to establish shifting pressures, and thereby bring about proper communication between the various ports of the sleeves which connect with the pump and with the suction and discharge ports.

More specifically the invention also resides in those novel features of construction, combination and arrangement of parts, all of which will be first fully described, and then be specifically pointed out in the appended claims, reference being had to the accompanying drawing, in which:—

Figure 1 is a vertical longitudinal section of my valve.

Figure 2 is a cross section on the line 2—2 of Figure 1.

Figure 3 is an elevation of the stationary sleeve.

Figure 4 is an elevation of the shiftable or floating sleeve.

Figure 5 is a diagrammatic view illustrating how the valve may be connected with a single cylinder pump.

Figure 6 is a diagrammatic view illustrating how the valve may be connected with a duplex pump.

Figure 7 is a diagrammatic view showing another way of connecting the valve with a twin-cylinder pump.

In the drawing, in which like numerals of reference designate like parts in all the figures, 1 is the casing-cylinder having a bore 2 and provided with a suction chamber 3 and discharge chambers 4 and 5 centrally located at either side of the suction chamber 3.

6 is the suction port through which the fluid is drawn into the valve and 7 and 8

are discharge ports through which the fluid is evacuated from the valve after passing through the pump.

The casing-cylinder 1 has end flanges 9 to which heads 10 are bolted or otherwise suitably secured, and these heads respectively have ports 11 and 12 for a purpose presently explained.

13 is a stationary sleeve which is provided with discharge ports 14 and 15 and suction ports 16 and 17. The stationary sleeve is held within the bore of the casing-cylinder and fits the outer surface of the cylinder head ring flanges 18.

19 is the shiftable or floating sleeve which is divided into two chambers by a central partition web 20. It also has suction ports 21 and 22 adjacent and to either side of the partition web.

By referring particularly to Figure 5, 23 designates a single acting pump of a usual type which has a suction plate 29 and a partition 30 dividing the pump transversely. 24 and 25 are ducts from the cylinder head ports 11 and 12 respectively to ports in the discharge valve plate 29 at either side of the partition 30. 26 is the discharge pipe or duct to the outlet duct 27 and 28 is the suction pipe which connects to port 6.

In Figure 6 the parts having the same purpose as those in Figure 5 bear the same reference characters plus the index letter "a," and in Figure 7 the parts having the same purpose as those in Figure 5 bear the same reference characters plus the index letter "b."

In operation, as the pump piston (or pistons) reciprocates suction or a negative pressure will be established at one side of the same and a positive pressure at the other side; these negative and positive pressures will respectively be communicated to the ends of the valve 1 and establish corresponding pressures within the valve at either side of the free or floating sleeve 19, thereby shifting the sleeve 19 to one or the other end of its stroke and line up the proper ports 16—20 or 17—21 as the case may be, and close off the proper sets of ports 14 or 16, it being understood that the valve sleeve 19 shifts with each stroke of the pump piston.

The valve sleeve 19 has its stroke limited by engagement with the flanges 18.

From the foregoing description taken in connection with the accompanying drawing, it is thought the complete construction, op-

eration and advantages of my invention will be clear, and I desire to say that slight changes in the details of construction to adapt the valve to particular kinds or makes of pumps may be made (such as variations in the numbers and areas of ports, size of cylinder and sleeves, etc.) without departing from the spirit of the invention or the scope of the appended claims.

10 What I claim is:

1. An automatic valve for pumps comprising a casing having suction and discharge ports, a floating valve sleeve having opposed chambers and ports to control said

15 suction and discharge ports, and means to connect said valve with a pump to establish suction and pressure alternately at the ends of said valve sleeve to shift the same.

2. In combination with a pump having a 20 cylinder and a piston, an automatic valve comprising a casing having suction and discharge ports, heads having ports connected with said pump at either side of the piston, a ported sleeve held within the casing and 25 having ports registering respectively with the suction and discharge ports of the casing, a shiftable sleeve within the ported sleeve and having a partition to divide it into two chambers one each communicating with the 30 head ports, and having ports to register with the discharge ports of the ported sleeve, said shiftable sleeve also adapted to control the suction ports of said ported sleeve.

3. An automatic valve comprising a casing-cylinder, heads secured to the ends of 35 said cylinder and each having a port opening into the cylinder, a fixed sleeve held within the cylinder, said cylinder having a central suction chamber and ports and a discharge chamber and port at each side of

said suction chamber, said sleeve having sets of ports registering one set with each discharge chamber and two sets registering with said suction chamber, a shiftable sleeve located within said fixed sleeve and itself having a partition dividing it into two chambers open at the ends of the sleeve, said shiftable sleeve having a set of ports from each chamber to register alternately with the sets of ports of the fixed sleeve 50 which register with the suction chamber, said shiftable sleeve being of a length to leave one set of discharge ports of the fixed sleeve open when the other set is closed.

4. An automatic valve comprising a casing-cylinder, heads secured to the ends of said cylinder and each having a port opening into the cylinder, a fixed sleeve held within the cylinder, said cylinder having a central suction chamber and port and a discharge chamber and port at each side of said suction chamber, said sleeve having sets of ports registering one set with each discharge chamber and two sets registering with said suction chamber, a shiftable sleeve located within said fixed sleeve and itself having a partition dividing it into two chambers open at the ends of the sleeve, said shiftable sleeve having a set of ports from each chamber to register alternately with the sets of ports of the fixed sleeve which register with the suction chamber, said shiftable sleeve being of a length to leave one set of discharge ports of the fixed sleeve open when the other set is closed, said heads having ring flanges to fit into the ends of the fixed sleeve and constitute stops for the shiftable sleeve.

LEROY M. PORTER.
